UNITED STATES PATENT OFFICE.

CLYDE C. VOGLESONG, OF OAKLAND, CALIFORNIA, ASSIGNOR TO AMERICAN COIN REGISTER COMPANY, A CORPORATION OF CALIFORNIA.

CHANGE-MAKING MACHINE.

1,168,582.

Specification of Letters Patent. Patented Jan. 18, 1916.

Application filed November 25, 1914. Serial No. 873,944.

To all whom it may concern:

Be it known that I, CLYDE C. VOGLESONG, a citizen of the United States, and a resident of Oakland, county of Alameda, and 5 State of California, have invented certain new and useful Improvements in Change-Making Machines, of which the following is a specification.

The invention relates to change making 10 machines adapted primarily to be used on street cars and other places where coins must be continually changed.

An object of the invention is to provide 15 a change making machine which will dispense the correct change for a coin of any denomination, preferably from ten cents to one dollar, in such denominations that the passenger receives coins of the proper denomination with which to pay his fare.

20 Another object of the invention is to provide means for locking the machine against use.

The invention possesses other advantageous features, some of which, with the foregoing, will be set forth at length in the following description, where I shall outline in full that form of the invention which I have selected for illustration in the drawings accompanying and forming part of the present 25 description.

The novelty of the invention will be included in the claims succeeding said description, and it is understood that by these claims, I desire to cover the invention in 30 whatever form it may be embodied. From this it will be apparent that I do not limit myself to the showing made by said drawings and description, as I may adopt many variations within the scope of my invention as expressed in said claims.

Referring to said drawings: Figure 1 is a vertical longitudinal section of the machine taken on the line 1—1 Fig. 2, the lower closing plate being removed to disclose the 45 interior, and certain portions being broken away to disclose the construction. Fig. 2 is a cross section of the machine taken on the line 2—2 Fig. 1. Fig. 3 is a cross section taken on the line 3—3 Fig. 1 showing the locking mechanism. Fig. 4 is a detail of the operating levers with the inclosing casting removed. Fig. 5 is a section taken on the line 4—4 Fig. 1. Fig. 6 is a rear view of the upper portion of the machine showing the springs which operate to return the 50

coin slides to their normal positions. Fig. 7 is a fragmentary cross section of one coin tube showing the ejecting slide in the operative position.

In pay-as-you-enter cars, which are 60 equipped with a fare box, the conductor usually returns to the passenger the entire change, allowing the passengers to deposit the fare in the fare box. In cars which are not so equipped, the conductor returns to the 65 passenger the change remaining after the fare has been deducted. The machine of my invention is adapted for either of these uses, and may be manipulated to deliver the total change for a coin or a predetermined fraction of the coin, permitting its employment with both systems. It is to be understood, however, that the use of the device is not limited to street cars, but that it may be employed in any situation where change 70 should be rapidly made.

The machine consists of a casing 7, having arranged therein a plurality of coin receiving tubes 8—9—10—11 of the proper diameter to correspond to the coins to be contained therein. The tubes are partly closed at their upper ends by a plate 12 which is provided with slotted bottom depressions 13, allowing the coins to be readily deposited in the tubes and preventing them from being dislodged from the tubes. The plate 12 is covered by a spring pressed hinged plate 14, which closes the depressions 13 and prevents the passenger from depositing coins in the change making machine, instead of in 80 the fare box. The change making machine is usually fastened to the fare box and mistakes in depositing coins are made by the passengers, when the coin receiving depressions of the change making machine are 85 visible and accessible. In the present embodiment of the invention, tubes 8 and 9 are arranged to contain nickels, tube 10, dimes, and tube 11, quarters.

Means are provided for ejecting the 100 proper number of coins from each tube to produce the desired change. Arranged at the lower ends of the tubes are a plurality of coin ejectors or slides, which when operated cause the desired number of coins to 105 be removed from the tubes. The slides are supported by a plate 15 which partly covers the lower opening of the tubes. The slides are preferably provided with apertures extending therethrough of substantially the 110

same diameter as the respective coins and the lower coin or coins in each tube seat in the apertures in the slides, so that they are moved transversely from the supporting plate 15 as the slides are moved.

5 The thickness of the respective slides in proportion to the thickness of the coins in the various tubes is determined by the change to be delivered. The present machine is constructed so that it may be operated to deliver at one time either two nickels, five nickels, two dimes and one nickel, a quarter, two dimes and one nickel, or three quarters, two dimes and one nickel. In order to accomplish these results the slide 16 under tube 8 is of the thickness of three nickels so that as the slide is moved transversely, three nickels are discharged from the stack in tube 8. Under tube 9 are two superposed slides 17—18, each of the thickness of one nickel, and means are provided for moving one or both of these slides. Under tube 10 is one slide 19 of the thickness of two dimes, and under tube 11 are two superposed slides 21 and 22, slide 21 being of the thickness of one quarter and slide 22 of the thickness of two quarters, and means are provided for moving either slide 21 or slides 21 and 22 at the same time. The slides under the various tubes are normally held in position with the apertures therein alined with the tubes by means of the springs 23 bearing against the ends of the slides and secured to the frame or body 7. 35 The lower slide, in those instances where two slides are positioned under one tube, is provided with a slot 24, to accommodate the spring bearing against the upper slide, when the lower slide only is moved.

40 Secured to the under side of each slide is a bifurcated cleat or channel 25 which is engaged by the operative means to produce the desired movement of the slide. Arranged below the slides and journaled in 45 the frame or body 7 is a compound shaft consisting of a plurality of telescopically arranged shafts, the shafts, with the exception of the central shaft, being concentric and annular. The shafts are partially cut away at different portions, and secured to each shaft is one or more pins which are adapted to engage the cleats 25 and move the slide or slides as the corresponding shaft is rotated. Secured to the inner shaft 26 are 50 two pins 27—28 which are arranged respectively to engage slides 16 and 18. Secured to the next shaft 29 is a pin 31 arranged to engage slide 18. Secured to the next shaft 32 are two pins 33—34 arranged respectively to engage slides 17 and 19. Secured to the next outer shaft 35 are three pins 36—37—38 arranged respectively to engage slides 17, 19 and 21, and secured to the outer shaft 39 are three pins 41—42—43 55 arranged respectively to engage the slides 60 65

17, 19 and 22. The pins project beyond the periphery of the outer shaft 39 and are of such length that when a shaft is partially rotated, the pin or pins move into engagement with the corresponding cleat or cleats, 70 and the further rotation of the shaft moves the slide or slides.

At one end, the shafts terminate in circular flanges 44, the flanges being of the same diameter and being spaced apart axially. 75 Secured to or formed integral with each flange is a lever 45, bearing on its end a disk 46 upon which is noted the change which will be produced by the operation of each lever. The levers 45 are bent at different 80 angles, so that the disks 46 are spaced apart a greater distance than the flanges 44, so that one lever may be readily selected, and the levers are preferably formed of different lengths for the same reason.

85 The various concentric shafts bear against each other over considerable areas, and the friction between the shafts is such that the rotation of one shaft may produce a rotation of one or more of the other shafts. To prevent this, means are provided for restraining the initial movement of the shafts. Surrounding and inclosing the flanges 44 is a casing 47 which is provided with slots through which the levers 45 extend. Secured to this casing are a plurality of springs 48, one for each flange 44, and each spring is provided on its end with a depression which normally engages a button or stop 49 on the corresponding flange. 90 Pressure is required to release the stop from the depression in the spring, and this pressure is sufficient to prevent those shafts, other than that one which is being directly rotated, from rotating.

95 Means are also provided for locking the keys or levers 45 so that the machine may not be operated. Pivotally arranged within the casing 47 is a latch 51 which overlies all of the flanges 44, and this latch is pressed toward the periphery of the flanges by the spring 52. Formed on the longitudinally disposed latch is a toe 53, which when engaged by the key 54 holds the latch away from the flanges. The key 54 is formed with a tapered end so that as it is moved into the casing 47 it engages the toe and moves the latch away from the flanges. When the key is withdrawn, the latch is pressed against the periphery of the flanges. 100 On the periphery of each flange is an abutment 55, which, coming in contact with the latch, prevents the shaft from being rotated.

105 In those instances where two slides are arranged under one tube, the lower slide 125 may be moved independently of the upper slide, but a movement of the upper slide causes a movement of the lower slide. The lower slide is provided with a slot or cut away portion through which the cleat on 110

the upper slide extends, so that as the upper slide is moved, it carries the lower slide with it.

I claim:

- 5 1. A change making machine, comprising a plurality of coin receiving tubes, a coin ejector arranged below each of said tubes, a plurality of concentric shafts arranged adjacent to said ejectors, pins on said shafts adapted to engage and operate certain predetermined ejectors, means for rotating any one of said shafts, and means for preventing the remaining shafts from being rotated by the rotation of said shaft.
- 10 2. A change making machine, comprising a plurality of coin receiving tubes, a coin ejector arranged below each tube, a plurality of concentric shafts arranged adjacent to said ejectors, means on said shafts adapted to engage certain predetermined ejectors, a flange on the end of each shaft, and springs engaging said flanges arranged to oppose rotation of the shafts.
- 15 3. A change making machine, comprising a plurality of coin receiving tubes, a coin ejector arranged below each tube, a plurality of concentric shafts arranged adjacent to said ejectors, means on said shafts adapted to engage certain predetermined ejectors and cause the discharge of certain coins for a rotation of the corresponding shaft, a flange on the end of each shaft, an abutment on each flange, a spring engaging each abutment and serving to oppose rotation of each shaft, and means for rotating said shafts.
- 20 4. A change making machine, comprising a plurality of coin receiving tubes, coin ejectors arranged below said tubes, a plurality of concentric shafts arranged adjacent said ejectors, pins on said shafts adapted to engage certain predetermined ejectors, means for rotating any one of said shafts, said

rotation serving to eject the desired coin or coins, and means for locking said shafts 45 against rotation.

5. A change making machine, comprising a plurality of coin receiving tubes, coin ejectors arranged below said tubes, a plurality of concentric shafts arranged adjacent said ejectors, means on said shafts adapted to engage certain predetermined ejectors, means for rotating any one of said shafts, said rotation serving to eject the desired coin or coins, an abutment on each of said 55 shafts, and a latch arranged to be moved into the path of said abutments and thereby lock said shafts against rotation.

6. A change making machine, comprising a plurality of coin receiving tubes, coin ejectors arranged below said tubes, a plurality of concentric shafts arranged adjacent said ejectors, and adapted by their individual rotation to eject the desired coin or coins, a flange on each of said shafts, an abutment 65 on each flange, and a latch adapted to be moved into the path of said abutments, and thereby lock the shafts against rotation.

7. In a change making machine, a plurality of coin receiving tubes, slides arranged under said tubes, a cleat secured to the underside of each slide, a plurality of concentric shafts telescopically arranged below said slides, pins on said shafts adapted to engage said cleats, and means for rotating 75 said shafts independently, rotation of a shaft serving to eject the desired coin or coins.

In testimony whereof, I have hereunto set my hand at San Francisco, California, 80 this 10th day of November, 1914.

CLYDE C. VOGLESONG.
